UNITED STATES PATENT OFFICE.

HARRY B. PAGE, OF EAST HAVEN, CONNECTICUT, ASSIGNOR TO SARGENT & COMPANY, OF NEW HAVEN, CONNECTICUT.

CYLINDER LOCK.

Application filed January 9, 1923. Serial No. 611,686.

This application relates to cylinder locks and more especially to the provision of an armored or hard metal front or casing for locks of this character, so that any attempt 5 to render the lock useless or ineffectual by drilling into the front thereof may be frustrated.

While I have shown pin tumbler locks in the drawings accompanying the application, 10 it will be understood that my invention is not limited in all of its aspects to such locks, but may be applied to other types of cylinder locks as well.

In some types of locks, and especially in 15 the case of pin tumbler locks, an intruder may, by drilling into the lock in the plane of the pins, cut off the row of pins and thereby render the lock useless, as the key plug may then be turned freely to unlock 20 the door. Such an operation is usually performed by drilling in through the face of the lock cylinder, which must necessarily be made of metal sufficiently soft to admit of being bored by a drill.

25 One object of my invention is to overcome the disadvantage named above and to provide a lock cylinder with a hard metal front which will withstand the action of a drill.

Another object of my invention is to provide 30 a lock with an armored front, of this character, secured or attached to the lock in a novel way.

A still further object of my invention is 35 to provide an armored lock cylinder of the character described, which shall be simple in construction and economical to manufacture and assemble.

To these and other ends, the invention 40 consists in the novel features and combinations of parts to be hereinafter described and claimed.

In the accompanying drawings:

Fig. 1 is a front elevational view of a lock cylinder embodying my invention;

45 Fig. 2 is a sectional view of line 2—2 of Fig. 1;

Fig. 3 is a sectional view on line 3—3 of Fig. 2;

50 Fig. 4 is a front elevational view showing the method of assembly of the parts of the lock;

Fig. 5 is a sectional view on line 5—5 of Fig. 3;

55 Fig. 6 is a sectional view on line 6—6 of Fig. 2 with the key barrel removed; while

Fig. 7 is a section through the hardened front plate of the lock corresponding to line 7—7 of Fig. 6, the lock cylinder being shown in elevation.

In the form of my invention which I have chosen to illustrate and describe, I have shown a lock cylinder at 10 provided with the usual pin tumbler openings 11, and a key barrel or plug 12 having the cooperating tumbler recesses or openings 13. The key 60 plug is formed with the usual key slot 14 so that when the proper key is inserted, it may be rotated within the cylinder 10, and a lug 15, eccentrically mounted upon the rear end of the key barrel, will 65 serve to raise a bolt or the like mounted in the recess 16 in the cylinder. To retain the key plug within the cylinder, a recess or slot 17 is formed in the plug and a pin or screw 18 is driven through the cylinder so that its 70 end will lie within this recess or slot.

At the front portion, the cylinder 10 may be formed with a narrow shoulder 20, the height of which will be equal to the thickness of the armored front 21, so that after the front 80 has been applied, the exterior of the cylinder will be of the same diameter throughout. Forwardly of this shoulder and at diametrically opposite portions, the cylinder may be cut away as at 22 and 23 in segmental form, and opening into these segmental recesses are slots 24 and 25, which slots do not, however, as clearly shown in Fig. 5, extend to the front face of the cylinder as do the cut-away portions 22 and 23. 85

The armored front 21 consists of a cup-shaped piece of hardened steel or the like having a front face of the same diameter as that of the body of the cylinder lock, and provided with a peripheral wall or flange 90 26 extending at right angles to the front face. Projecting inwardly from this flange or wall are a pair of oppositely disposed lugs 27 and 28 which may be formed so that their lengths are substantially equal to the altitudes of the segments 22 and 23. 95

This front plate is provided with an opening 29 through which the key barrel extends, and this opening is so disposed relatively to the lugs 27 and 28 that it will be in alignment with the key barrel opening in the lock cylinder when the lugs 27 and 28 are located in the grooves 24 and 25. 105

When the parts are made in the manner described, and it is desired to assemble the 110

hardened steel front upon a cylinder the cup-shaped member is placed by a longitudinal thrust upon the shouldered end of the cylinder with lugs 27 and 28 in the segmental cut-out portions 22 and 23 as shown in Fig. 4. It will be apparent that when the parts are in this position, a relative rotative movement will move the lugs from the cut-out portions 22 and 23 into the notches or slots 24 and 25 from which they cannot be dislodged by a direct longitudinal pull. In fact the armored front can only be removed by a reverse rotative movement which again disposes the lugs in the cut-out portions 22 and 23. With the parts in the position shown in Fig. 3 wherein the lugs are engaged in the slots, the opening 29 in the armored front is opposite the key plug opening in the cylinder, and if the key plug is now inserted, its head 31, which lies within the opening 29, will prevent a reverse or any further rotation of the armored front. The withdrawal of the key plug will then be prevented by the insertion of the key plug pin 18, and the parts will be effectually and permanently assembled in a very convenient and satisfactory manner.

It will be seen that while the armored front described will protect the pin tumblers which are located in the cylinder, the tumblers which are within the key barrel will not be so protected, due to the fact that they will lie opposite the opening 29. In order to protect the tumblers in the key barrel from the drilling operation described, a pin 32 of hardened steel or the like may be inserted in the head or shoulder at the front of the key barrel and in alignment with the pin tumblers therein. It will then be impossible to drill through the line of tumblers in the key barrel as the drill, upon striking this pin, will be unable to pierce it and will be diverted to one side, and thus will not sever the pin tumblers of the lock. It will be apparent that the recessed or cut-out portions 22 and 23 provide longitudinal passage ways upon the periphery of the lock which communicates with the peripheral grooves 24 and 25 in a manner similar in many respects to the longitudinal and transverse grooves which formed a part of the joint usually termed a bayonet joint. In other words, it may be correctly stated that the front plate and applicant's lock is secured upon the cylinder by means of a bayonet joint.

While I have shown and described a preferred embodiment of my invention, it will be understood that it is not limited to all the details shown, but is capable of modification and variation within the spirit of the invention and within the scope of the appended claims.

What I claim is:

1. A lock cylinder and a hardened plate

for the front of said cylinder, and cooperating engaging means upon said cylinder and plate whereby said plate may be applied directly to the cylinder and then rotated to a locking position.

2. A lock cylinder and a front plate for the same, said plate having an axially projecting flange extending along the curved surface of the cylinder and cooperating means upon said cylinder and flange whereby the plate may be applied to the cylinder by a longitudinal thrust and then rotated to a locking position.

3. A lock cylinder and a front plate for the same, said cylinder and plate having cooperating grooves and lugs whereby they may be secured together by a relative rotative movement.

4. A lock cylinder and a front plate therefor, said plate having a circumferential flange adapted to extend along the body of the cylinder, said flange and cylinder having cooperating grooves and projecting lugs whereby they may be secured together by a relative rotative movement.

5. A lock cylinder and a hardened front plate for the same, said plate having a circumferential flange adapted to lie along the body of the cylinder, a lug provided upon said flange, and a lug receiving groove provided in the periphery of the cylinder whereby the plate may be attached thereto.

6. A lock cylinder and a front plate therefor, said cylinder having a transverse groove formed therein adjacent one end thereof and a passage way leading into said groove from the front edge of the cylinder, and said plate having a lug to enter said passage way and groove.

7. A lock cylinder and a hardened front plate therefor, said cylinder having a peripheral groove formed therein adjacent one end thereof and a passage way leading into said groove from the front edge of the cylinder, and said plate having a lug to enter said passage way by a direct longitudinal thrust whereby it may then be rotated in said groove.

8. A lock cylinder provided with a transverse groove and a passage way leading from the front face of the cylinder into said groove to provide an attaching means for a plate.

9. A lock cylinder and a hardened front plate therefor, means to secure said plate upon the cylinder by a rotative movement, and means to prevent a reverse rotation and removal of said plate.

10. A lock cylinder and a hardened front plate therefor adapted to be applied to the cylinder by a direct longitudinal thrust and then rotated to a locking position, and means to prevent a reverse rotation of said plate to prevent its removal from the cylinder.

11. A lock cylinder, a hardened front plate

therefor adapted to be applied to the cylinder by a direct longitudinal thrust and then rotated to a predetermined position, and means to secure the plate against rotation from this position.

5 12. A lock cylinder and a hardened front plate therefor, both said members having openings adapted to be aligned with each other to receive a key barrel, means for securing the plate to the cylinder when the former is applied to the latter, and rotated to bring said openings into alignment, and means to prevent further rotation of said plate.

15 13. A lock cylinder and a hardened front plate adapted to be applied thereto by a longitudinal thrust, both said members being provided with openings to receive a key barrel, means to permit such application only when said openings are out of alignment, said plate being then rotatable to align said openings, and means to secure the plate upon the cylinder in said position of alignment.

25 14. A lock cylinder and a hardened front plate therefor, said plate being adapted to be secured thereon by a rotative movement, both said members having key barrel receiving openings which are aligned when said plate is secured upon said cylinder, and a key barrel secured in said openings to prevent rotation of the parts from said position.

35 15. A lock cylinder and a hardened front plate therefor, said cylinder being provided with a peripheral groove and a longitudinal passage way opening into said groove from the front face of the cylinder, said plate being provided with a lug to enter said passageway and then to be rotated in said groove, both said cylinder and plate being provided with key barrel openings which are eccentric when the lug is in said passage way, but which may be aligned by the rotation of the lug in the groove and a key barrel inserted in said aligned openings to prevent rotation of the plate from said position.

45 16. In a lock, a lock cylinder, a hardened front plate therefor, and secured thereto by a bayonet joint.

50 17. In combination, a lock cylinder, a protective facing therefor provided with a peripheral flange, said cylinder being telescopically received in the flange, and means effective after a relative rotation of the parts to lock the facing to the cylinder.

55 18. In combination, a lock case, a protective facing therefor, both of said members being provided with key barrel openings, interengaging means upon said case and facing to secure the two together, said means being capable of disengagement to permit separation of the parts only when the key barrel openings are out of register.

19. In combination, a lock case, a protective facing therefor secured thereto by a rotative movement, a key barrel mounted in openings in said case and facing, and means including said key barrel to prevent removal of the facing from the case.

20. A lock cylinder and a protective facing therefor, said facing being applied directly to the cylinder and then rotated through a partial revolution, and means effective upon said rotation to prevent separation of the facing and cylinder.

25 21. A lock cylinder and a hardened front plate therefor, said cylinder having a peripheral groove formed therein adjacent one end thereof, and a passageway leading into said groove from the front edge of the cylinder, the plate being provided with a lug to enter said passageway and groove, said plate and cylinder being provided with openings to accommodate a key barrel, and said openings being out of alignment when said lug registers with the passageway.

22. In combination with a lock case, a protecting armor therefor, said armor comprising a portion encircling said case and inturned portions at each end of said encircling portion to engage the case to limit movement of the armor thereon.

25 23. A lock case and a protecting armor therefor, said armor comprising a portion encircling the case, and a face portion extending over the face of the case, an inturned lug at the rear end of said encircling portion to enter a recess in the case to secure the armor thereon.

30 24. In combination, a lock cylinder, a protecting armor therefor, said armor comprising a cylindrical portion encircling the cylinder, and having means at each end thereof extending inwardly to embrace a part of the lock cylinder therebetween to prevent removal of the armor.

35 25. A lock cylinder and a front plate therefor, said cylinder and plate having cooperating means whereby they may be secured together, said means being adapted to be brought into engagement by a rotative movement of said plate on said cylinder, and means to prevent reverse rotation of the plate.

40 26. In combination, a lock cylinder, a protective face member therefor provided with a flange extending axially of the cylinder, said face member being applied to the cylinder with the latter and the flange in telescopic relation, and means effective after a relative rotation of the parts to lock the face member to the cylinder.

45 In witness whereof, I have hereunto set my hand on this 4 day of January, 1923.

HARRY B. PAGE.
